UNITED STATES PATENT OFFICE

IRVING GOLDSMITH, OF FREEPORT, NEW YORK, ASSIGNOR TO ALADDIN IRON WORKS, INC., OF NEW YORK, N. Y., A CORPORATION OF NEW YORK

DESIGN FOR A SEAT

Application filed June 16, 1931. Serial No. 40,226. Term of patent 3½ years.

To all whom it may concern:

Be it known that I, IRVING GOLDSMITH, a citizen of the United States, and a resident of Freeport, in the county of Nassau and State of New York, have invented the new, original, and ornamental Design for a Seat, of which the following is a specification.

Reference is had to the accompanying drawing, in which—

The figure is a perspective view of a seat showing my new design.

I claim:

The ornamental design for a seat substantially as shown.

IRVING GOLDSMITH.
